UNITED STATES PATENT OFFICE

103,651

DESIGN FOR A COIN BANK

David H. Zell, Brooklyn, N. Y.

Application December 2, 1936, Serial No. 66,251

Term of patent 14 years

To all whom it may concern:

Be it known that I, David H. Zell, a citizen of the United States, residing at Brooklyn, in the county of Kings and State of New York, have invented a new, original, and ornamental Design for Coin Banks, of which the following is a specification, reference being had to the accompanying drawing forming part thereof.

Fig. 1 is a front elevation of a coin bank, showing my new design.

Fig. 2 is a top plan view thereof.

Fig. 3 is an end elevation.

The numerals shown in Fig. 1 are merely representative and do not constitute an essential feature of the invention.

I claim:

The ornamental design for a coin bank, as shown and described.

DAVID H. ZELL.
